[57] **CLAIM**

The ornamental design for a crossarm for vineyard support system, as shown and described.

DESCRIPTION

FIG. 1 is a front perspective of a crossarm for vineyard support system, showing my new design;

FIG. 2 is a front elevational view to an enlarged scale;

FIG. 3 is an elevational view of one edge, to an enlarged scale, the opposite edge being a mirror image;

FIG. 4 is a rear elevational view to an enlarged scale;

FIG. 5 is an elevational view of one end, to a greatly enlarged scale, the opposite end being a mirror image;

FIG. 6 is a front perspective view of a modification of a crossarm for vineyard support system;

FIG. 7 is a front elevational view;

FIG. 8 is an elevational view of one edge, the opposite edge being a mirror image;

FIG. 9 is a rear elevational view; and,

FIG. 10 is an elevational view of one end, to an enlarged scale, the opposite end being a mirror image.
